Primary Examiner—Paula A. Greene

(57) **CLAIM**

The ornamental design for an recreational vehicle screen door latch actuator, as shown and described.

DESCRIPTION

FIG. 1 is a front elevational view of our design;
FIG. 2 is a rear elevational view of our design;
FIG. 3 is a left side elevational view of our design;
FIG. 4 is a right side elevational view of our design;
FIG. 5 is a top plan view of our design; and,
FIG. 6 is a bottom plan view of our design.

1 Claim, 2 Drawing Sheets

FIG. 1

FIG. 2

FIG. 3

FIG. 4

FIG. 5

FIG. 6
